BUBBLE CAP AND RISER TUBE ASSEMBLY

Raymond R. Collins, Southport, Conn., and
Wheaton W. Kraft, Scarsdale, N. Y., assignors
to The Lummus Company, New York, N. Y., a
corporation of Delaware

Application December 18, 1947, Serial No. 792,566

3 Claims. (Cl. 261—114)

1

This invention relates to bubble cap and riser tube assemblies, and more particularly to the construction and arrangement of the several parts thereof whereby a bubble cap may be supported from and attached to a riser tube which is preferably permanently mounted through or at an opening in the deck, plate or tray of a bubble tower or the like.

More particularly the invention relates to a construction in which upward extensions from the top edge of the riser tube cooperate with the under surface of a bubble cap for supporting the same and in which projections thereon extend through perforations in the cap to receive fastening means for engaging the upper surface of the cap for holding it in position on the riser tube.

It is a general object of the present invention to provide a novel and improved assembly of riser tube and bubble cap permitting ready separation when desired.

More particularly it is an object of the invention to provide, in an assembly of the type described, a combined riser tube and bubble cap support, portions of which extend through the bubble cap and are perforated to receive wedges for cooperation with the surface of the cap to hold it in position on the riser.

One of the features of the invention resides in the construction of a riser tube with extensions having surfaces for engagement in a plurality of positions with the under side of the bubble cap for supporting the same, certain of which are fitted with projections for passing through openings in the cap top and adapted to receive wedges for clamping the cap against these surfaces to rigidly position it on and in respect to the riser tube.

An important feature of one embodiment consists in the formation of a blank of sheet metal for bending into a riser tube, the blank having a maximum length equivalent to the circumference of the tube and having its upper edge provided with serrations which alternately form deep notches and extensions whereby, when the blank is curled into a tube and welded to close the side seam, a riser capable of supporting a bubble cap is formed.

In accordance with another embodiment an important feature includes the use of radially positioned supports and fastening means secured to the outer surface of the riser tube and preformed to engage and accurately position the bubble cap both in vertical and lateral directions.

A still further important generic feature of the

2

invention resides in the provision of supporting and holding means for the bubble cap which leave the entire interior and the lower exterior portion of the riser tube entirely clear and free of obstructions, whereby it may be more readily cleaned and reconditioned after use.

Other and further objects and features of the invention will be more apparent to those skilled in the art on a consideration of the accompanying drawing and following specification wherein are disclosed two exemplary embodiments of the invention, with the understanding that such modifications and combinations thereof may be made as fall within the scope of the appended claims without departing from the spirit of the invention.

In said drawings:

Fig. 1 is a vertical central section through a bubble cap and riser tube assembly constructed in accordance with the present invention mounted on a bubble deck, the view being taken on line 1—1 of Fig. 2;

Fig. 2 is a top plan view of the assembled bubble cap and riser tube;

Fig. 3 is a perspective view on an enlarged scale of one of the hold-down wedges;

Fig. 4 is a fragmentary view of a riser tube blank illustrating both the hold-down type and plain cap supports;

Fig. 5 is a view similar to Fig. 1 showing a modification of the cap supporting means; and

Fig. 6 is a top plan view of the modification of Fig. 5.

Because of the wide use of bubble caps in various chemical processes, in distillation towers and oil refining equipment and the like, there has sprung up an active demand for improved constructions. Bubble caps are used in enormous quantities in some of the large towers and cost becomes one of the important considerations in selecting their form. Another factor is the ease of initial installation and the facility with which they can be removed, cleaned and replaced.

Bubble caps are mounted on trays, decks or plates, horizontally positioned and arranged in stories in large diameter towers. They are preferably spaced apart, only a sufficient distance to allow a workman to move about between the decks. He therefore should be required to give a minimum of attention to the application of the caps to the risers to insure that all are properly positioned and fastened. It is extremely important that the caps can be placed or removed by working entirely from one side of the deck.

Because of the factors of corrosion, erosion

and deposition of hardened or gummy materials or the like, simplicity is required in the hold-down means and replacement costs must be kept low.

In accordance with the present invention these important features are all achieved in a simple bubble cap assembly comprising a tube which may be rolled from a sheet metal blank, welded into form and attached to the deck at an opening therein by welding or by some of the rolling or spinning processes. It cooperates directly to support the bubble cap and portions pass through the material of the cap to receive hold-down wedges.

One form of the invention is shown in Figs. 1 to 4, inclusive, of the drawings, and illustrated as mounted on a metal plate or deck 10 of conventional form, over which liquid is constrained to flow by some such means as illustrated in the patent to Holmes et al, No. 1,965,549. The liquid level is preferably maintained at about that shown by line L. To prevent the liquid from passing through the many apertures 12 in the deck through which the gas or vapor rises, each is fitted, in a fluid-tight manner, with a riser tube 13 extending about the opening and having its upper end positioned above the level of the line L. Such a tube here is shown as of relatively thin sheet metal welded as at 14 where it passes through the metal of the deck. Any approved form of attachment at this point is contemplated, but it is preferred that the attachment be relatively permanent.

In general the top surface 15 of the tube is horizontal and spaced somewhat above the line L. It is broken, however, by a plurality, preferably 4, extensions 16 spaced 90° apart and having substantially flat upper surfaces 17 adapted to be received beneath the under face of the flat top wall 18 of the bubble cap 19, which in the form illustrated is a sheet metal stamping comprising the central flat top portion 18, the vertical skirt portion 20 and the curved joining fillet 21. In accordance with the customary practice the lower edge of the skirt may be dentated or serrated as at 22 to break up the gases or vapors passing beneath the surface of the liquid, into small bubbles for more intimate contact on rising through the liquid. The specific shape and structure of the bubble cap forms no particular part of the present invention.

Fig. 4 illustrates a fragment of a blank from which the riser tube may be fabricated. It comprises a section of suitable sheet metal 24 having a length equivalent to the circumference of the finished tube, preferably having a straight bottom 25 and a top comprising alternate notches 26 and the extensions 16 previously referred to, properly spaced apart and provided with the upper surfaces 17 for engagement beneath the cap. Where four of these are provided, alternate ones are equipped with integral projections 28 of reduced cross-section. The upper ends are preferably rounded as at 29 for convenience in the later assembly of the bubble cap thereon, and each is transversely apertured as at 30 by an elongated vertical slot. The blank after being punched or die cut is rolled into a tube and the abutting ends welded to form a gas-tight structure.

Each bubble cap is provided through its top wall adjacent the junction with the fillet 21 with a pair of apertures 31 diametrically disposed and accurately positioned to receive the projections 28. The holes are of such size as to be substan-

tially filled by these projections whereby but little gas may escape.

Bubble caps when assembled over their respective riser tubes rest substantially uniformly on four surfaces 17 spaced 90° apart and are stabilized and accurately positioned in respect to the liquid level and the deck surfaces whereby all bubble caps function as nearly uniformly as possible. Two of the projections, it will be seen, 10 serve only to position the cap in the vertical direction, but the other two determine its horizontal positioning. After the cap is in position, wedges such as shown at 33 in Fig. 3 are driven radially inwardly through the slots 30 until they 15 become tight. Their under surfaces 34 engage the top wall of the cap and press it downwardly so that the under wall engages on the shoulders 17 and holds the cap rigidly in position. For 20 purpose of removal, when it is necessary to clean the deck and caps, a relatively light blow with a hammer or appropriate use of a bar serves to pry the wedges loose and they can be removed and the caps lifted off. Any wedges which might be lost or damaged are easily replaced since they 25 are cut from cheap metal.

It will be noticed that in this form there is no obstruction whatsoever to the interior or exterior of the tubular riser so that when the cap is removed cleaning is facilitated. There is a 30 minimum of obstruction to the flow of gas or vapor from the interior to the exterior of the tube because of the large areas of the notches 15 between the extensions 16.

In the embodiments of Figs. 5 and 6 the major 35 parts are substantially the same in construction as already described with these differences: the riser tube 50 has its upper surface 51 cut off square throughout and the bubble cap has openings 52 therein differently disposed than those 40 in the first embodiment.

The means for supporting the cap from the tube comprises sheet metal brackets 53 and 54, the first being provided in an opposed pair which are curved on their upper surfaces to conform 45 to the fillet of the cap. In common with the ones numbered 54 they are notched at 55 to a horizontal depth equivalent to the thickness of the wall of tube 50. This notch sets over the top edge of the tube with the bracket radially 50 disposed and it is there welded permanently to the tube. The brackets 54 have the projections 57 extending upwardly therefrom for passing through the openings 52 in the cap. These are slotted as in the first embodiment to receive 55 wedges as shown. These wedges 33 instead of extending radially as in the first embodiment are more or less tangential to the projection of the riser tube 50, as seen in Fig. 6, offering a somewhat better chance to drive them out because the two do not interfere with each other in the manipulation of a hammer.

This embodiment, it will be seen, leaves the interior of the tube free and clear for cleaning and offers somewhat less restriction to the gas 65 flow because of the thinness of the brackets 53 and 54 in the path of the gas flow. The brackets are positioned well above the lower portion of the tube so as not to interfere with brushes or the like cleaning the upper surface of the deck and the outer periphery of the tube.

We claim:

1. A bubble cap structure comprising in combination an internally unobstructed tubular riser element, a bubble cap disposed over the 70 upper end of said riser element, a plurality of

flat, tongue-like, cap-supporting members integrally secured to said riser element and extending outwardly and upwardly therefrom in radial planes, at least two of said supporting members being oppositely disposed, each being provided with an end portion of reduced width having an aperture therethrough, said bubble cap being provided with perforations formed and arranged to snugly receive the respective apertured end portions, and a wedge received in the aperture of each end portion and engaging the top of said cap to detachably secure the cap in fixed relation to the riser.

2. A bubble cap structure comprising in combination an internally unobstructed tubular riser element, a bubble cap disposed over the upper end of said riser element, a plurality of flat, tongue-like, cap-supporting members integrally secured to said riser element and extending outwardly and upwardly therefrom in radial planes, at least two of said supporting members being oppositely disposed, each being provided with an end portion of reduced width having an aperture therethrough, said bubble cap being provided with perforations formed and arranged to snugly receive the respective apertured end portions, and means external to said cap engaging said members and said cap to detachably secure the cap in fixed relation to the riser.

3. A bubble cap structure comprising in combination an internally unobstructed tubular riser element, a bubble cap disposed over the upper end of said riser element, a plurality of flat,

tongue-like, cap-supporting members integrally secured to said riser element and extending outwardly and upwardly therefrom in radial planes, at least two of said supporting members being oppositely disposed, each being provided with a laterally extending edge directly engaging the under side of the cap and supporting the same elevated above said riser, an end portion of reduced width on each of said supporting members, said end portion having an aperture therethrough, said bubble cap being provided with perforations formed and arranged to snugly receive the respective apertured end portions, and a wedge received in the aperture of each end portion and engaging the top of said cap to detachably secure the cap in fixed relation to the riser.
